United States Patent Office

Des. 231,695
Patented May 28, 1974

231,695

SHELTER

Richard Dattner, 180 Cabrini Blvd.,
New York, N.Y. 10033

Filed Sept. 11, 1972, Ser. No. 287,943

Term of patent 14 years

Int. Cl. D25—03

U.S. Cl. D13—1 D

FIG. 3

FIG. 2

FIG. 1 is a front and left side perspective view of a shelter embodying my new design;

FIG. 2 is a rear elevational view thereof; and

FIG. 3 is a right side elevational view thereof.

I claim:

The ornamental design for a shelter, as shown.
